UNITED STATES PATENT OFFICE.

LEVI J. MASTERSON, OF PHILADELPHIA, PENNSYLVANIA, ASSIGNOR TO
GEORGE H. ORCUTT, GEORGE HARDING, AND RUDOLPH M. HUNTER, ALL
OF SAME PLACE.

ROLLING-MILL.

SPECIFICATION forming part of Letters Patent No. 267,983, dated November 21, 1882.

Application filed June 30, 1882. (No model.)

To all whom it may concern:

Be it known that I, LEVI J. MASTERSON, of the city and county of Philadelphia, and State of Pennsylvania, have invented an Improvement 5 in Rolling-Mills, of which the following is a specification.

My invention has reference to rolling-mills, but more particularly to the mechanism by which the rod which is being rolled is given a 10 partial revolution; and it consists in the arrangement of a series of pairs of rolls for reducing the metal, having their axes horizontal, in combination with a series of pairs of feed-rolls whose operative surfaces are constituted 15 of spring-threads arranged about their peripheries, and having their axes oblique or vertical, a pair of said feed-rolls being arranged between every two pairs of reducing-rolls, and in many details of construction, all of which are 20 fully set out in the following specification, and shown in the accompanying drawings, which form part thereof.

The object of my invention is to cause a partial rotation of the bar which is being rolled, 25 and during its passage from one pair of rolls to the next, whereby all of the said rolls may be arranged with their axes horizontal, which position is necessary for economical working and keeping of the rolls cool, the said partial 30 rotation being effected by suitable spring feed-rollers, which automatically adjust themselves to the bar to be turned.

In the drawings, Figure 1 is a vertical section through a series of reducing and feed rolls. 35 Fig. 2 is a front elevation of my improved feed-rolls. Fig. 3 is a plan of same. Fig. 4 is an elevation of a spring-thread, made square in cross-section. Fig. 5 is a similar view in which the thread is made triangular, and Fig. 6 is a 40 similar view in which the thread is made substantially parabolical.

A A' A² A³ are the reducing-rolls, and are arranged in pairs, one above the other, their axes being horizontal.

45 B B' B² are the feed-rolls, and are also arranged in pairs, each pair being arranged between two pairs of reducing-rolls, as shown, having their axes vertical or oblique.

50 C C' C² C³ represent the bars in the act of being rolled.

The feed-rolls are constructed as follows:

Two cylindrical bodies, F, are journaled rigidly or adjustably at each end f to the frame E, open at the top between the two journals f, as shown at E'. The bottoms of these bodies 55 F are provided with flanges or collars H, which may be provided with lips h, if desired, to prevent displacement of the end of the spring threads or helices I, which encircle the said bodies and rest upon the flanges or collars. 60 These spring helices or threads may be of any desired cross-section, the drawings showing elliptical or oval, square or rectangular, triangular, and parabolic sections. In practice I prefer the oval or elliptical, as shown in Fig. 65 2. These spring helices or threads are clamped in place by screw-nut G, which is locked in place by a lock-nut, G', these nuts working on screw-threads F' upon the upper end of the bodies F. Any other well-known means may 70 be employed to hold the springs in place, and the device as a whole may be made adjustable, so as to set it for any desired pitch of thread, which may be varied by said nuts.

In arranging the feed-rolls between the main 75 or reducing rolls I prefer to gradually decrease their obliquity in accordance with the variation of the pitch of the spring-threads; but even this is not absolutely necessary, inasmuch as the elasticity in the threads causes them to adjust themselves automatically to any sized or shaped bar. The reducing-rolls reduce the bar to a flattened oval or analogous shape, and before passing to the next pair of reducing-rolls the feed threads or helices cause it to be 80 turned a quarter of a revolution, so as to be fed with its widest section in a vertical or nearly vertical line, so that when passed through the next pair of reducing-rolls it is again flattened, each successive flattening and reduction taking 85 place at right angles to that which took place immediately before.

Having now described my invention, what I claim as new, and desire to secure by Letters Patent, is—

1. In a rolling-mill, a series of horizontal rolls, in combination with a series of feed-roll bodies, said feed-roll bodies being arranged in pairs, and having spring feed-threads about their peripheries, substantially as and for the 90 purpose specified.

2. In a rolling-mill, a series of horizontal re-

reducing-rolls, in combination with a series of oblique feed-roll bodies, said feed-roll bodies being arranged in pairs between every two pairs of reducing-rolls, and having spring feed-threads about their peripheries, substantially as and for the purpose specified.

3. In a rolling-mill, a series of horizontal reducing-rolls, in combination with a series of oblique feed-roll bodies, said feed-roll bodies being arranged in pairs between every two pairs of reducing-rolls, having spring feed-threads about their peripheries, and a gradually-decreasing obliquity, substantially as and for the purpose specified.

4. In a rolling-mill, a series of pairs of horizontal reducing-rolls, in combination with a series of twisting and feeding rolls, said feed-rolls being arranged in pairs between every two pairs of reducing-rolls, and each successive pair having axes of a gradually-decreasing obliquity and approaching the vertical line, substantially as and for the purpose specified.

5. A pair of horizontal reducing-rolls, in combination with a pair of twisting feed-rolls arranged in front of same, and adapted to feed the bar to said reducing-rolls, and at the same time turn the said bar a part of a revolution, said rolls being provided with elastic helical feed flanges or ribs, substantially as and for the purpose specified.

6. A pair of feed-roll bodies provided with devices to feed the bar to a pair of reducing-rolls, and at the same time give said bar a partial rotation, said devices consisting of elastic

helical feed flanges or ribs, in combination with means to change the pitch of said helical ribs, substantially as and for the purpose specified.

7. A pair of horizontal reducing-rolls, in combination with a pair of roll-bodies having twisting feed devices arranged in front of same, and adapted through said devices to give the bar a partial revolution as it is being fed to the said reducing-rolls, said devices consisting of elastic helical flanges or ribs, the ribs of both of said helices being either right or left handed, substantially as and for the purpose specified.

8. A pair of feed spirals or helices having elasticity, and arranged to rotate in opposite directions, and between which the bar is fed, whereby the said bar is fed horizontally, and also turned a part of a revolution, substantially as and for the purpose specified.

9. In a rolling-mill, the feed-roller bodies F, provided with shoulders or flanges H, in combination with nuts G G', or their equivalent, spring threads or ribs I, and frame E, substantially as and for the purpose specified.

10. The frame E, having opening E' at top, in combination with roller-bodies F and their spring threads or ribs I, substantially as and for the purpose specified.

In testimony of which invention I hereunto set my hand.

LEVI J. MASTERSON.
